CANDY WRAPPING MACHINE

Theodore F. Schlicksupp, Long Island City, N. Y.

Application May 4, 1951, Serial No. 224,594

13 Claims. (Cl. 53—42)

1

This invention relates to machines for individually wrapping small articles, and more particularly to machines for wrapping pieces of candy.

The principal object of the invention is to provide an improved candy wrapping machine adapted to wrap pieces of candy fed to and through the machine in rapid succession without at any time stopping the progressive movement of the pieces of candy through the machine thereby giving the machine a large capacity.

Another object of the invention is to provide a candy wrapping machine which is especially adapted for wrapping fragile pieces of candy such as chocolate covered cherries without damaging or injuring them.

A further object is to provide a candy wrapping machine having improved mechanism for feeding to the machine a continuous strip of the wrapping material, such as metal foil, and for cutting from the strip pieces of suitable length for wrapping the individual pieces of candy.

Still another object is to provide a candy wrapping machine of the kind referred to in the preceding paragraph having the necessary adjustments whereby the machine can wrap lots of candy in which the pieces in one lot differ in size, within certain limits, from those in another lot, and whereby the feeding and cutting mechanism for the wrapping material will so feed and cut it that the pieces cut from the strip of wrapping material will have the proper length for the pieces of candy being wrapped.

Other objects of the invention will appear from the following detail description of the machine.

A candy wrapping machine embodying the invention is illustrated in the accompanying drawings, in which:

Figure 1 is a plan view of the machine.

Fig. 2 is a vertical section through the entire machine excepting the feeding mechanism for the metal foil, the section being taken on the line 2—2 of Fig. 1.

Fig. 3 is a partial horizontal section taken on the line 3—3 of Fig. 2, certain portions being broken away to expose underlying parts.

Fig. 4 is a horizontal section taken on the line 4—4 of Fig. 2, certain portions being broken away to expose underlying parts.

Fig. 5 is a perspective view of the cam that operates the foil gripping fingers.

Fig. 6 is a horizontal section taken on the line 6—6 of Fig. 2 with certain portions broken away to expose underlying parts.

Fig. 7 is a horizontal section taken on the line 55

2

7—7 of Fig. 2, a portion of the foot treadle there-in shown being broken away to expose underlying parts.

Fig. 8 is a plan view of the foil feeding and cutting mechanism showing a strip of foil being fed forward by it so that an end portion of the strip will lie over a piece of candy to be wrapped and so that when the end portion of the strip is severed by the cutting knives the severed piece of foil will be in a centered or symmetrical relation with the piece of candy.

Fig. 9 is a view similar to Fig. 8 showing the foil feeding and cutting mechanism delivering larger pieces of foil for wrapping larger pieces of candy.

Fig. 10 is a vertical section through the foil feed rolls and cutting knives, the section being taken on the line 10—10 of Fig. 8.

Fig. 11 is a front elevation of the foil cutting knives.

Fig. 11a is a horizontal section taken on the line 11a—11a of Fig. 10.

Fig. 12 is a side elevation of the upper portion of the foil feeding and cutting mechanism.

Fig. 13 is an end elevation of the foil feeding and cutting mechanism as viewed from the end where the cutting knives are located.

Fig. 14 is a vertical section taken on the line 14—14 of Fig. 13.

Fig. 15 is a view corresponding to the upper portion of Fig. 14 showing the parts in a different position.

Fig. 16 is a horizontal section through the cam shaft of the foil feeding and cutting mechanism, the section being taken on the line 16—16 of Fig. 13.

Fig. 17 is a horizontal section taken on the line 17—17 of Fig. 13 showing the rocker arm shaft of the foil feeding and cutting mechanism and the rocker arms with their cam follower rollers mounted on the shaft.

Fig. 18 (on the same sheet as Fig. 1) is a plan view of part of the mechanism which causes foil to be fed by the foil feeding mechanism only when a piece of candy is present in the next pocket of the carrier disc approaching the foil feeding mechanism.

Fig. 19 is a vertical section through the foil feeding and cutting mechanism taken on the line 19—19 of Fig. 13, showing the parts adjusted for delivering the largest piece of foil that the mechanism is capable of delivering.

Fig. 20 is a view corresponding to the upper portion of Fig. 19 showing the parts adjusted for delivering the smallest piece of foil that the mechanism is capable of delivering.

Fig. 21 is a side elevation, partly in section, of one of the ball clutches forming part of the foil feeding mechanism.

Fig. 22 is an enlarged vertical section taken on the line 22—22 of Fig. 20.

Fig. 23 is a side elevation of the yielding roller under which each piece of wrapped candy passes as it is being discharged from the machine to compress the inwardly folded portions of the foil under the piece of candy.

Fig. 24 is a plan view of one of the rubber candy-gripping rings in its normal or contracted condition in which it is capable of gripping a piece of candy.

Fig. 25 is a view corresponding to Fig. 24 showing the rubber ring expanded to a size which permits it to receive or discharge a piece of candy.

Fig. 26 is a partial vertical section showing the cutting knives cutting a piece of foil from the end of the strip and showing a piece of candy being moved into position under the severed piece of foil, the direction of movement of the piece of candy in this view being away from the reader.

Fig. 27 is a vertical section taken approximately on the line 27—27 of Fig. 26 showing the piece of candy (now moving toward the left in this figure) an instant before it is moved onto a plunger which will raise it into contact with the severed piece of foil.

Figs. 28, 29 and 30 are vertical sections similar to Fig. 27, Fig. 28 showing the piece of candy just after it is completely moved onto the above-mentioned plunger, Fig. 29 showing it after it has been raised by the plunger into contact with the severed piece of foil, and Fig. 30 showing the piece of candy and the piece of foil being pushed upwardly by the plunger through one of the brush rings that folds the foil down around the piece of candy.

Fig. 31 is a vertical section showing the piece of candy and the folded down foil being pushed upwardly still farther by the plunger into one of the candy grippers.

Fig. 32 is a vertical section showing the piece of candy and the folded down foil just after being gripped by the candy gripper, the plunger having receded in this view, and

Fig. 33 is a diagrammatic development view showing the sequence of operations during the wrapping of a piece of candy in a piece of metal foil.

In general, the machine in its preferred form comprises a rotary carrier disc having a series of open-bottom pockets. This disc rotates over a stationary candy supporting surface such that pieces of candy to be wrapped and that are fed by the operator successively into the pockets as they pass in succession past a candy feeding station are each slid by the carrier disc over the stationary surface along a circular path to the opposite side of the machine where the metal foil is fed to the machine. Here a continuous strip of the metal foil is fed forward toward the center of the machine at right angles to the path along which each piece of candy travels as it passes the foil feeding mechanism.

Each piece of candy moves under a portion of the foil strip that has been fed forward and the leading edge of the foil strip is held down by gripper fingers while a pair of knives sever from the foil strip a piece of foil in which is to be wrapped the piece of candy lying under the severed piece of foil. At this time, and while the piece of candy is still being moved in its circular

path, one of a circular series of vertically movable plungers which are carried by a rotary structure and that move past the foil feeding mechanism in the manner hereinafter described, rises through an arcuate slot in the support on which the piece of candy has been moving up to this time and the piece of candy moves onto the upper end of the plunger.

The plunger lifts the piece of candy into contact with the severed piece of foil and then lifts both the piece of candy and the piece of foil and pushes them through a brush ring having inwardly extending bristles which fold the piece of foil down around the piece of candy as the piece of candy rises through the brush ring. One of these brush rings is mounted on the above-mentioned rotary structure above each of the plungers. Mounted on this rotary structure above each of the brush rings is a candy gripping device into which the piece of candy with its folded down piece of foil is pushed by the plunger after it is pushed through the brush ring.

The candy gripping device then grips the piece of candy after which the plunger recedes leaving the piece of candy suspended by the candy gripping device. Each of the plungers when it reaches this position is lowered below the support on which each piece of candy slides during the first 180° of its travel and continues its movement to the place where it is again raised to pick up the piece of candy to be wrapped.

The piece of foil in which each piece of candy is wrapped is of such size that when it is folded down over a piece of candy the foil extends downwardly a short distance below the bottom of the piece of candy and the four corners of the piece of foil point downwardly in the nature of flaps. The candy gripper in which the piece of candy is now gripped, and which is now continuing the movement of the piece of candy in its circular path, is then rotated about its own axis $\frac{1}{8}$ of a revolution. This is to bring one of the downwardly extending flaps or corners of the piece of foil to a position in which it is at the forward or leading side of the piece of candy.

Immediately thereafter the piece of candy approaches a wiping blade which is lifted so that it wipes against the leading downwardly extending flap or corner on the piece of foil and folds it back to a position in the same plane as the bottom of the piece of candy. The instant this is accomplished the wiping blade is lowered so as not to disturb the other downwardly extending flaps or corners of the piece of foil. During further movement of the piece of candy in the candy gripping device the piece of candy is turned about its own axis 90° to bring the next downwardly extending flap or corner of the piece of foil to the leading side of the piece of candy and this flap is similarly folded under by a second wiping blade.

This operation is repeated until all four flaps or corners of the piece of foil have been folded under the piece of candy into parallel relation with the bottom of the piece of candy. Each piece of candy thus wrapped is then discharged onto a rotary disc which moves the wrapped pieces of candy successively under a yielding roller which gives a final compression or creasing action to the folded under flaps whereupon the pieces of candy are deflected off of this rotating disc and collected at a discharge point.

The above-mentioned rotary structure which carries the vertically movable plungers, the

brush rings, and the candy grippers, rotates about an axis which is in eccentric relation with the axis about which rotates the carrier disc that slides the pieces of candy along the supporting surface up to the foil feeding mechanism; and the plungers, brush rings, and candy grippers are mounted on the rotary structure so they all move in a circular path having a smaller diameter than the diameter of the circular path in which the pieces of candy are moved by the carrier disc. The relationship between the parts is such that as the pockets on the carrier disc move past a feed table from which the operator deposits pieces of candy in them they travel along an arcuate path which lies outwardly of the arcuate path along which the various devices on the rotary structure move at this part of the machine.

In other words, while the candy pockets on the carrier disc are moving past the feed table they project out from under the rotary structure and the parts carried by it so as to give the operator free access to them. However, at the opposite side of the machine, where the foil feeding mechanism is located, the arcuate paths of the plungers on the rotary structure and the candy pockets on the carrier disc coincide throughout a short distance so that each candy pocket moves a piece of candy directly over one of the plungers until the plunger rises and lifts the piece of candy clear of the candy pocket and into contact with the severed piece of metal foil as above described.

In the particular machine illustrated in the drawings there are twelve candy pockets in the carrier disc and eight sets of plungers, brush rings, and candy grippers. Therefore, to bring one of the candy pockets with its piece of candy to a position in front of the foil feeding mechanism simultaneously with one of the plungers the carrier disc and the rotary structure carrying the plungers, brush rings, and candy grippers, are located at a speed ratio of 8:12.

The foil feeding and cutting mechanism has an adjusting handle the position of which determines the amount of foil fed forward in a given time and the position of the cutting knives relative to the path followed by the piece of candy as it passes under the piece of foil cut off by the knives. When the machine is used for wrapping relatively large pieces of candy the handle is adjusted to increase the amount of foil fed forward in a given time and to move the cutting knives rearwardly away from the path of travel of the piece of candy. This causes a larger piece of foil to be severed from the foil strip which extends an equal distance inwardly and outwardly of the piece of candy. When the machine is used for wrapping smaller pieces of candy the handle is adjusted in the opposite direction to feed a smaller amount of foil forward in a given time and to move the cutting knives closer to the path of travel of the piece of candy.

Still another feature of the machine is the provision of means whereby no metal foil will be fed forward by the foil feeding mechanism if there is no piece of candy in the next pocket of the carrier disc which is approaching the foil feeding mechanism.

The main frame 1 of the machine (Fig. 2) supports a casting 2 the upper wall of which constitutes the above-mentioned support on which the pieces of candy rest as they are being moved from the feed table to the foil feeding and cut-

ting mechanism. The feed table is shown at 3 and is in the nature of a shelf supported by the machine frame. The rotary carrier disc which moves the pieces of candy while they are supported on the upper surface of the casting 2 is shown at 4. The foil feeding mechanism is represented by broken lines at the right of Fig. 2 and is denoted in general by the reference numeral 5.

10 The carrier disc 4 is supported near its outer periphery on pins 6 (see also Fig. 6) which are carried by the casting 2 and which project a short distance above the upper surface of this casting. The carrier disc 4 has a central opening 7. An internal annular gear 8 is connected to the inner edge portion of the carrier disc 4 and rests in a recess 9 formed in the upper inner edge of the annular casting 2. The gear 8 is rotatably supported in this recess and is driven in the manner hereinafter described. The pins 6 and the gear 8 support the carrier disc 4 so that it is spaced a slight distance above the upper surface of the casting 2 as shown in Fig. 2. When the gear 8 is rotated it rotates the carrier disc 4 and the outer edge of the carrier disc slides on the supporting pins 6.

As best shown in Figs. 1 and 6 the carrier disc 4 has a circular series of pockets 10 each of which is adapted to receive one of the pieces of candy 30 to be wrapped. The pockets 10 are bottomless in that they do not support the pieces of candy but they are each shaped to fit the contour of one of the pieces of candy to be wrapped while the piece of candy is actually supported on the upper surface of the casting 2. Each of the 35 pockets is preferably formed in a small removable disc 11 (Figs. 1, 2 and 6) fitting in an opening in the main carrier disc 4. This makes it possible to remove the discs and replace them by another 40 set having pockets of the appropriate shape and size to accommodate the shape and size of the particular pieces of candy to be wrapped by the machine.

45 The pockets should have a size and shape such that each pocket, when a piece of candy is placed therein by the operator, will sufficiently confine the piece of candy to guide it to the proper position to be picked up by one of the rising plungers previously referred to. Each of the small 50 discs 11, as best shown in Figs. 26-30, has a peripheral flange 12 by which it is supported by the main carrier disc 4. Each disc 11 is held in proper fixed position with respect to the main carrier disc 4 by a removable pin inserted through 55 the edge of the main disc 4 and projecting into a recess in the edge of the disc 11. One of these pins is shown in dotted lines at 13 in Fig. 6.

The main carrier disc 4 also has a series of 60 slots 14 extending through it (Fig. 6). These slots are substantially tangential to the inner opening 7 in the carrier disc and each of them at its outer end joins the pocket 10 in one of the small discs 11. These tangential slots accommodate the vertically movable plungers as will 65 hereinafter appear.

In order to facilitate positioning and removal of the carrier disc 4 it is preferably divided into several sections, the particular carrier disc shown in the drawings being divided into three sections 70 each of which has a circumferential extent of about 120°. Each section is supported at its outer edge by the above-described pins 6 projecting upwardly from the casting 2, and is connected at its inner edge to the annular gear 8 by upwardly 75 projecting pins 15 (Fig. 2) carried by the gear

and fitting in corresponding openings in the section of the carrier disc. Thus, the carrier disc sections can be lifted out of place leaving the gear 8 undisturbed.

The frame 1 of the machine supports a fixed center post 16 (Figs. 2 and 6) which passes upwardly through the center opening 7 of the carrier disc. Rotatably mounted on the post 16 is a sleeve 17 on the lower end of which is fitted a plunger-carrying casting 18 (Fig. 2) which rotates with the sleeve. A number of plunger guide tubes 19 are each supported at its upper end by this casting. A plunger 20 is mounted to slide vertically in each of the tubes 19. At its upper end each plunger has an enlarged head 21 adapted to support one of the pieces of candy to be wrapped as will hereinafter appear.

A cam roller 22 is attached to the lower end of each of the plungers 20. Each of the plunger guide tubes 19 has a vertical slot 23 in its outer side to accommodate the mounting pin or axle of the corresponding cam roller 22 and thus permit the plunger within the guide tube to move vertically in it. The cam rollers 22 are actuated by a cam track 24 mounted on the frame 1 and which encircles the machine.

Located just above the plunger casting 18, and also fitted on the sleeve 17 so that it rotates unitarily with the plunger casting, is another casting 25 to which is connected a circular series of brush rings 26 (see also Fig. 4). One of these brush rings is located above each of the plungers 20. Each brush ring has bristles 27 mounted in it which extend radially inward toward the center of the ring.

Above the brush ring casting 25 there is another casting 28 (Fig. 2) which is also fitted on the sleeve 17 so that it rotates in unison with the plunger casting and the brush ring casting. A number of guide tubes 29 are each supported near its lower end by this casting 28. One of these guide tubes is located directly over and concentric with each of the brush rings. A cam rod 30 is mounted to slide vertically in each of the guide tubes 29 and has a cam roller 31 secured to it the mounting pin or axle of which passes through a vertical slot 32 at the outer side of the guide tube. The lower end of each cam rod 30 carries a cam 31a having the shape shown in Fig. 2 and also in Figs. 26, 31 and 32. The cam rollers 31 are actuated by a cam track 33 which encircles the machine and which is carried by an upper stationary casting 34 secured to the upper end of the post 16 by set screws 35 (Fig. 2).

Rotatably mounted on the lower end of each of the cam rod guide tubes 29 is a Geneva wheel 36 (Fig. 2). Four candy gripper arms 37 are located under each Geneva wheel, each arm being pivoted at its upper end to a suspension member 37a (see also Fig. 3) secured to the Geneva wheel at its lower side. The lower ends of the arms 37 carry a candy gripping rubber ring 38. One of these rubber rings is shown in plan view in Fig. 24. It has four radially projecting ears 39 each having an opening to receive the lower end of one of the arms 37.

Each of the pivot pins 40 which suspends one of the candy gripper arms 37 from the suspension member 37a also suspends a cam roller arm 41 (Fig. 2) having at its lower end a cam roller 42 adapted to be actuated by the cam 31a. Each cam roller arm 41 has pivotal movement about the axis of the pivot 40 independently of the corresponding candy gripper arm 37, but, as shown in Fig. 31, when the cam roller arms 41 are moved

outwardly by the cam 31a, each of them imparts outward movement to the corresponding candy gripper arm 37 by means of a pin 43 on the cam roller arm which engages the inner end of an adjustable set screw 44 on the corresponding candy gripper arm.

This causes the lower ends of the candy gripper arms 37 to stretch or expand the rubber candy gripping ring 38 from the position shown in Figs. 10 and 32 to the position shown in Figs. 25 and 31. When the cam 31a releases the cam roller arms 41 the rubber ring 38 returns to its normal position and thereby returns the arms 37 and 41 to their normal positions. By adjusting the set screws 44 the position of the lower ends of arms 37 may be varied to accommodate them to candy gripping rings 38 of different sizes.

The brush ring casting 25 also supports a thin annular plate 45 (Fig. 2) spaced a short distance above the carrier disc 4. This plate has a circular series of openings 46 (see also Fig. 4) each of which lies directly over one of the plungers 20, and constitutes a shelf onto which the forward end of the foil strip F is fed by 25 the feed rolls 47 and 48 of the foil feeding mechanism as shown in Fig. 2. By the time a predetermined amount of metal foil has been fed onto the plate 45 one of the openings 46 therein lies directly under the portion of the foil strip that 30 is so fed onto the plate 45 and which will be cut off by the cutting knives.

A circular series of foil gripping devices 49, one of which appears in plan view in Fig. 4, are each pivotally supported by the brush ring casting 25 (Fig. 2), there being one of these foil gripping devices adjacent each opening 46 in the plate 45. Each foil gripping device 49 has two foil gripping fingers 50 (Fig. 4) at the end of each of which there is a button 51 of soft material such as rubber (Fig. 2). Each foil gripping device is pivoted intermediate its ends on a depending support carried by the brush ring casting 25, and is actuated by a rod 52 pivoted to it (Fig. 2) and which is guided at its lower end in the brush ring casting 25 and at its upper end in the next higher casting 28. A stationary cam sleeve 53 (Fig. 2) secured to the post 16 has a cam face 54 at its lower edge which actuates the rods 52. This cam sleeve is shown by itself in Fig. 5.

The cam face 54 is so shaped that after a predetermined amount of metal foil has been fed forward by the feed rolls 47 and 48 over one of the openings 46 in the plate 45 the corresponding foil gripping device 49 is actuated to lower its gripping fingers into contact with the forward edge portion of the metal foil. This is immediately after the forwardly fed portion of the metal foil has been severed from the main strip of foil. Thus, as soon as a piece of foil has been severed from the main strip, it is gripped against the plate 45 by one of the foil gripping devices and the piece of foil therefore moves along with the plate 45 until one of the plungers 20 lifts a piece of candy into contact with the severed piece of foil and starts lifting the piece of foil upwardly along with the piece of candy. At this time the foil gripping device is again actuated to release its grip on the piece of metal foil.

The rotary brush ring casting 25 also supports a cam ring 55 (Fig. 2). The upper edge of this ring constitutes a cam face which actuates the wiper blades that fold in the corners of the metal foil which extend down below the piece of candy after the piece of candy and the piece of metal foil have been pushed up through the

brush ring to thereby fold the piece of foil down around the piece of candy. There are four of these wiper blades each designated 56 in Fig. 4. Their exact location circumferentially of the machine will be made clear later on. Each wiper blade is carried by an arm 57 pivoted on a horizontal pin 58 (see also Fig. 2) which extends inwardly from a bracket arm 59 that is attached to and depends from the upper stationary casting 34. Each of the arms 57 that carries one of the wiper blades 56 also carries a cam follower roller 60 (Figs. 2 and 4) which is actuated by the cam ring 55. This cam ring raises and lowers each wiper blade 56 at the proper time as will be clear when the operation of the machine is later described.

The machine is driven from an electric motor 61 (Fig. 2) mounted so that its armature rotates about a vertical axis. A drive pulley 62 is secured to the upper end of the armature shaft and is connected by means of a belt 63 with a driven pulley 64 which rotates about the axis of a vertical drive shaft 65 rotatably mounted in the frame of the machine. The pulley 64 may be operatively connected to and disconnected from the drive shaft 65 by a friction clutch which constitutes no part of the invention and therefore need not be described in detail. It is sufficient to note that when a foot treadle 66 is in the position shown in Fig. 2 the friction clutch is engaged and the pulley 64 then imparts rotation to the drive shaft 65. When the foot treadle 66 is moved counterclockwise about the axis of its shaft 67 the friction clutch is disengaged and the rotating pulley 64 will then not impart rotation to the drive shaft 65. The foot treadle 66 remains in either position to which it is moved by the operator.

The upper end of the drive shaft 65 has secured to it a pinion 68 which meshes with an internal gear 69 secured to the under surface of the plunger casting 18. Thus, when the drive shaft 65 is rotating it rotates the annular gear 68, the plunger casting 18, the sleeve 17, and all of the other parts mounted on this sleeve including the brush ring casting 25 and the casting 28 which carries the candy grippers and the cam rods 30. The plungers, the brush rings, the plate 45 onto which the metal foil is fed, the foil grippers, the cam ring 55 which actuates the wiper blades, the candy grippers, and the cam rods 30 therefore all rotate in unison. The parts which do not rotate include the cam track 24 which actuates the plungers 20, the casting 2 on whose upper surface the pieces of candy are moved by the carrier disc from the feed table to the foil feeding mechanism, the feed table 3, the foil feeding and cutting mechanism, the wiper blades that are actuated by the cam ring 55, the cam sleeve 53, and the cam track 33 which actuates the cam rods 30.

It should be noted that the recess 9 in the casting 2 that guides and supports the annular gear 8 for driving the carrier disc 4 is in eccentric relation with the axis of the post 16 about which rotate all rotary parts of the machine except the carrier disc 4. This eccentric relation is such that the carrier disc 4 rotates about an axis which is closer to the feed table 3 than is the axis of the post 16 about which the other rotary parts rotate. Also, the radius of the circular path followed by the plungers, brush rings, candy grippers, etc. is smaller than the radius of the circular path followed by the feed pockets 10 in the carrier disc 4.

The arrangement is such that these two circular paths are superimposed throughout a short distance as each plunger moves past the foil feeding mechanism. Thus, each piece of candy is brought by one of the pockets to a position over one of the plungers 20 while the plunger is moving in front of the foil feeding mechanism. This will be clear from Figs. 1 and 6. Fig. 1 also makes it clear that because of the arrangement just described the pockets 10 in the carrier disc 4 when moving past the feed table 3 will project out beyond the other parts of the machine thus giving the operator free access to the pockets so that he can easily deposit a piece of candy in each pocket as it passes the feed table.

The internal gear 8 which is connected to the carrier disc 4 is driven by a gear 70 secured to the plunger casting 18. Thus, rotation of this casting imparts rotation to the carrier disc 4. 20 In the particular machine illustrated in the drawings there are twelve pockets in the carrier disc 4 but only eight sets of plungers, brush rings, and candy grippers. The gears 70 and 8 are therefore so related that the speed ratio between the 25 carrier disc 4 and the rotating structure which carries the plungers, etc. is 8:12 and this causes one of the pockets in the carrier disc to bring a piece of candy to a position in front of the foil feeding mechanism at the same time that one 30 of the plungers reaches a position under this piece of candy.

While the plungers 20 are moving from the feed table to the opposite side of the machine where the foil feeding mechanism is located they 35 are in their lowered position so that the heads 21 on the plungers move under the top wall of the casting 2. When each plunger is raised at the foil feeding station to push a piece of candy and a piece of foil through the brush ring and into 40 one of the candy grippers the plunger must, of course, be permitted to project through the upper wall of the casting 2 and for this reason an arcuate slot 71 (Fig. 6) is provided in the upper wall of this casting which extends from a position in 45 front of the foil feeding mechanism in a counterclockwise direction in Fig. 6 through almost 180°.

This permits each plunger while revolving about the axis of the post 16 to be raised from its lowest position (in which the head on the plunger 50 is below the upper wall of the casting 2) to its highest position in which it moves the piece of candy into the rubber candy gripping ring 38 and then back to its lowest position in which the head of the plunger is again below the upper wall of 55 the casting 2. A small thin rectangular plate 72 (Figs. 1 and 6) is secured to the upper surface of the casting 2 so that it lies over the leading end of the arcuate slot 71 in front of the foil feeding mechanism. As will hereinafter appear, each 60 piece of candy as it is pushed along the surface of the casting 2 slides over this plate 72 and during this time one of the plungers moves up so that its head lies close to the under surface of the plate 72 and then moves horizontally so that 65 as the plunger head emerges from under the plate 72 the piece of candy being pushed off of it moves gently onto the head of the plunger without a precipitous drop.

The foil feeding and cutting mechanism is 70 illustrated in Figs. 1 and 8-22, inclusive. It has two side plates 73 and 74 (Figs. 1, 8, 9, 12, 13, 19, 20 and 22) which are secured at their forward ends to the main frame of the machine. There is a notch 75 in the upper edge of each plate near 75 its outer end as best shown in Fig. 12. These

notches are in transverse alignment and support the spindle or axle 76 of a roll 77 of metal foil in strip form. The strip of foil F passes from the roll 77 under a roller 78, between the feed rolls 47 and 48, and thence through the cutting knives hereinafter described (see particularly Fig. 12).

The lower feed roll 48 is rotatably mounted in a pair of side plates 79 (Figs. 8-10, 12, 19, 20 and 22) at the outer side of each of which there is secured a rack 80 having teeth on its under surface. These racks are supported by and slide longitudinally in a pair of blocks 81 (see particularly Fig. 22) one of which is secured to the inner side of one outer plate 73 of the foil feeding mechanism and the other of which is secured to the inner side of the other outer plate 74, each of the blocks 81 having a longitudinal recess 82 in its inner face to receive the corresponding outwardly projecting rack 80. Thus, the blocks 81 constitute stationary guides in which the racks 80 and the framework which supports the lower feed roll can slide longitudinally.

A portion of each block 81 is cut away at its under side as shown in Figs. 19 and 20 to expose some of the teeth at the under side of each rack and a pinion 83 meshes with each rack where its teeth are thus exposed (Figs. 19 and 20). The two pinions 83 are mounted on a shaft 84 journalled at its ends in the main side plates 73 and 74 of the foil feeding mechanism. The shaft 84 has secured to it a handle 85 (Figs. 1, 12, 19 and 20). This handle may be rotated throughout 90° to any one of a number of selected positions between the dotted line position shown in Fig. 19 and the dotted line position shown in Fig. 20. A pin at the end of the handle removably engages in one of an arcuate series of openings 86 in each of its selected positions to retain the handle in the position to which it has been moved. Rotation of the handle in either direction adjusts the frame carrying the lower feed roll either forward or backward a predetermined amount depending upon the position to which the handle 85 is turned.

A pair of rods 87 and 88 (Figs. 1, 12, 19 and 20) extend between the side plates 79 that rotatably support the lower feed roll. The axis of these rods lie in the same horizontal plane and the rods are spaced apart longitudinally of the foil feeding mechanism. The innermost one of these rods appears in Fig. 22 and as best shown in this figure the rods are clamped between the plates 79 by screws 89. The rods pass through a block 90 the upper surface of which constitutes a support for the strip of foil F as it is passing to the feed rolls 47 and 48 as shown in Fig. 10.

The rods 87 and 88 also pass through a pair of plates 91 and 92 (Figs. 1, 19, 20 and 22) which extend downwardly some distance below the block 90 as best shown in Fig. 22 where they support, among other things, the gears which drive the feed rolls. As also best shown in Fig. 22 the plates 91 and 92 are held against the side faces of the block 90 and in spaced relation with the plates 79 that carry the lower feed roll by a pair of spacing sleeves 93. Thus, the block 90 and the plates 91 and 92 at its opposite sides move unitarily with the plates 79 that support the lower feed roll and these parts are adjusted longitudinally of the foil feeding mechanism by turning the handle 85.

The upper feed roll 47 is rotatably carried between the inner ends of a pair of arms 94 and 95 (Figs. 4, 12, 19 and 20). These arms are se-

cured to the ends of a shaft 96 which is rotatably mounted in a pair of ears 97 (Figs. 1, 12, 19 and 20) which extend outwardly from the block 90. Thus, when the plates 79 (in which the lower feed roller is mounted) and the block 90 are adjusting longitudinally of the foil feeding mechanism by turning the handle 85 the shaft 96 on which the supporting arms 94 of the upper feed roll are mounted also moves with them.

A depending arm 98 is secured at its upper end to the central portion of the shaft 96 as best shown in Figs. 1, 19 and 20. This arm is pivotally connected at its lower end to the core of an electric solenoid 99 (Fig. 19) which is attached to the depending plates 91 and 92. Thus, when these plates are moved by the handle 85 the solenoid moves with them. When the solenoid is energized it swings the arm 98 to the broken line position shown in Fig. 19 and hence turns the shaft 96 and swings the arms 94 and 95 about the axis of this shaft to lift the upper feed roll 47 out of contact with the strip of foil being fed between the two feed rolls. A coil spring 100 returns the arm 98 and the upper feed roll to normal position when the solenoid is de-energized. However, gears 101 secured to the upper feed roll 47 at its opposite ends remain in mesh with corresponding gears 102 secured to the lower feed roll 48 at its opposite ends. When the lower feed roll is driven by the gears herein-after described the upper feed roll is therefore driven from it even when the feed rolls are slightly separated by energization of the sole-noid 99.

A rocker arm 103 is pivotally mounted intermediate its ends at the inner side of each of the main side plates 73 and 74 (Figs. 19 and 20). One end of each of the rocker arms is provided with a slot 104 and its other end is pivotally connected to the upper end of a link 105. The lower end of each link 105 (Fig. 19) is pivotally connected to a rocker arm 106 (Fig. 19). As shown in Fig. 17 the two rocker arms 106 are each mounted to oscillate freely on a sleeve 107 surrounding a rocker arm shaft 108 which is secured at its ends to the main side plates 73 and 74 (see also Figs. 13 and 19). Each rocker arm 106 carries a roller 109 constituting a cam follower.

Secured between the main side plates 73 and 74 just below the rocker arm shaft 108 is a cam shaft 110 (Figs. 13 and 19). A rotatable sleeve 111 (Fig. 16) is mounted on the shaft 110 and near each end of this sleeve is secured a cam 111a secured to it and which is driven from a pinion 111b on the vertical drive shaft 65 of the machine (Figs. 2 and 19). Each of the cams 111a actuates one of the cam follower rollers 109 to oscillate the corresponding rocker arm 106 and thereby oscillate the corresponding rocker arm 103 through one of the links 105 (Fig. 19). A coil spring 106a is connected to each link 105 to keep the corresponding cam follower roller 109 in engagement with its cam 111a. For a reason which will later appear the two cams 111a are angularly displaced relative to each other so that the rocker arms 103 (Fig. 9) oscillate in opposite directions throughout most of their movement.

Referring to Fig. 22, there is clamped at the outer side of each of the plates 91 and 92 (constituting part of the structure which moves with the feed rolls when they are adjusted longitudinally of the foil feeding mechanism), a cup-like member 113. A gear 114 is rotatably mounted

on each of these cup-like members, one of these gears meshing with the gear at one end of the lower feed roll and the other meshing with the gear at the other end of the lower feed roll. Secured to the gear 114 is the inner member 115 of a ball clutch shown by itself in Fig. 21. An outer member 116 of the ball clutch has a hub portion 117 rotatably fitting within the cup-like member 113.

At the periphery of the inner member 115 of the ball clutch there are a number of clearances 118 (Fig. 21) each providing an inclined surface 119 in opposed relation to an interior cylindrical surface 120 on the outer member 116 of the ball clutch. In each of the clearances 118 there is positioned a spring pressed ball 121. The arrangement is such that if the outer member 116 of the clutch is rotated in a counter-clockwise direction as viewed in Fig. 21 it will impart rotation to the inner member 115 of the clutch, but rotation of the outer member in the opposite direction will not impart rotation to the inner member. The outer member of the clutch carries a pin 122. One of these pins appears in Fig. 19, and it will be seen from this figure that the pin engages in the slot 104 of one of the rocker arms 103 above described.

The cams 112 which operate the rocker arms 103 are angularly displaced on the shaft 109 slightly less than 180° . Therefore, during the major part of the movement of the rocker arms 103 one rocker arm will be moving one pin 122 in a direction to rotate the feed rolls through the corresponding ball clutch while the other rocker arm will be moving the other pin 122 in a direction that will not rotate the feed rolls through the corresponding ball clutch, but the joint action of the two rocker arms 103 will cause continuous rotation of the feed rolls except for a brief interval of time during which the two rocker arms are simultaneously moving in a direction in which neither ball clutch will transmit rotation to the feed rolls. The forward feeding of the strip of metal foil will therefore be momentarily interrupted during this brief interval, and it is at this time that the cutting knives sever a piece from the end of the foil strip.

The cutting knives comprise a fixed plate 123 and a relatively movable plate 124 (Figs. 10 and 11). The fixed plate has an elongated horizontal slot 125 the upper edge of which is beveled to form a knife edge 126. The movable plate 124 slides against the inner face of the fixed plate 123 and has a beveled upper edge 127 which constitutes a knife edge which cooperates with the knife edge 126 on the fixed plate 123. It is apparent that when the foil strip is fed through the slot 125 and the movable plate 124 is moved upwardly the two cutting edges will sever a piece from the end of the foil strip F as depicted in Fig. 10.

The mounting for the knife plates comprises a U-shaped member 128 (Fig. 8) which extends between the side plates 79 in which the lower feed roll is mounted. It is secured between these plates by screws 129. The foil strip F passes under the central portion of this U-shaped member through a suitable clearance which is provided for this purpose. Extending transversely of the feed mechanism under the member 128 is a block 130 (Fig. 10) which is attached at its ends to the ends of the member 128 by vertical screws 131 (Figs. 8 and 10). In this way the block 130 is supported by the U-shaped member 128. The upper surface of the block 130 constitutes a sup-

port for the strip of metal foil after it leaves the feed rolls 47 and 48.

Bearing against the inner side of the movable knife blade 124 is a transversely extending bar 132 (Figs. 8, 10 and 11a). Two screws 133 are screwed into this member and extend horizontally and outwardly from it. They pass through openings in both knife blades and are each surrounded by a sleeve 134 (Figs. 10 and 11a). Each screw 133 with its sleeve extends into a cavity 135 formed in the outer vertical face of the block 130. The rear end of each sleeve 134 has a shoulder 136 between which and the bottom of the cavity 135 a coil spring 137 is positioned.

The coil springs 137 thus yieldingly urge the screws 133 and their sleeves 134 outwardly causing the bar 132 to press the movable knife blade 124 into close contact with the stationary knife plate 123. That side of the bar 132 which is adjacent the movable knife plate has a series of projections 132a (Fig. 11a) which engage the surface of the movable knife plate at small areas thereby reducing the amount of friction between this bar and the movable knife plate. The projections 132a engage the surface of the movable knife plate at regions which lie between the openings in this plate as shown in Fig. 11a. Since the sleeves 134 on the screws 133 pass through openings in the fixed knife plate 123 with a close fit they constitute a fixed support for this knife plate. They pass through vertically elongated slots 138 (Fig. 11) in the movable knife plate 124 in such a way that this knife plate is permitted to move vertically throughout a limited distance but is restrained against lateral movement.

The movable knife plate 124 is provided at each end with a circular opening 139 (Fig. 11). These openings receive the inner ends of a pair of actuating arms 140 (Fig. 11) which are pivotally mounted at their outer ends on the shaft of the lower feed roll as best shown in Fig. 19. The inner end of each arm 140 where it engages in the circular opening 139 in the movable knife plate has a spherical contour as viewed in vertical cross section thus providing a kind of ball-and-socket connection between each of the arms 140 and the movable knife plate. The two arms 140 are interconnected by a cross rod 141 (Figs. 11 and 19) which in turn is connected by means of a link 142 to a rocker arm 143 (Fig. 19) mounted on the central portion of the previously described rocker arm shaft 108 (Figs. 13 and 17). This rocker arm is keyed to the sleeve 107 which surrounds the rocker arm shaft (Fig. 17).

The rocker arm 143 carries a cam follower roller 144 which engages at its periphery in a circumferential groove 145 (Figs. 14 and 16) formed in the periphery of a cam 146 secured to the sleeve 111 that rotates on the cam shaft 110. A pin 147 extends transversely through the cam 146 so that it extends laterally across the circumferential groove 145 in the periphery of the cam. Thus, as will be apparent from Fig. 14, the pin 147 constitutes the dwell on the cam. When the pin engages the cam follower roller 144 on the rocker arm 143 it momentarily lifts the rocker arm (Fig. 14) and moves the movable knife plate 124 upwardly to sever the foil strip. The movable knife blade is returned to normal position and the cam follower roller 144 is yieldingly held in engagement with the cam 146 by a coil spring 148 (Fig. 14) which acts on the end of an arm 149 also keyed to the sleeve 107 on the rocker arm shaft 108 (Fig. 17). This arm 149 performs another function as will later appear.

It will be noted from the foregoing description that the knives are mounted on the movable structure which may be adjusted inwardly or outwardly, i. e., toward or away from the main portion of the machine by movement of the handle 85.

In addition to the parts above described the foil feeding mechanism includes a pair of guide plates 150 and 151 (Figs. 1, 8 and 9). These plates have openings in them to receive the cross rods 87 and 88 (Fig. 1) on which each of the plates may slide transversely of the foil feed mechanism. A transversely extending adjusting shaft 152 (Fig. 8) is mounted to rotate in the plates 79 that carry the lower feed roll and extends loosely through the block 90 (Fig. 10). It has oppositely threaded end portions 153 and 154 (Fig. 8) each of which has threaded engagement with one of the guide plates. By turning a knob 155 on the end of the shaft 152 the two guide plates 150 and 151 may be simultaneously adjusted toward or away from each other to accommodate foil strips of different widths. As best shown in Figs. 1, 8 and 19 the guide plates have portions which extend outwardly far enough to engage the sides of the supply roll 77 of metal foil and thereby maintain this roll of foil in a central position in the foil feeding mechanism.

As each piece of candy approaches the foil feeding mechanism it engages the curved end of a foil-feed control arm 156 (Fig. 1) which is pivoted to swing in a horizontal plane about a fixed pivot 157. As will soon appear, when a piece of candy is present in the particular pocket of the carrier disc that is passing the curved end of the arm 156 the piece of candy will press outwardly on this arm and cause the strip of metal foil to be advanced by the feed rolls while the piece of candy is moving toward the foil feeding mechanism, but if no piece of candy is present in such pocket then the arm 156 will be permitted to swing inwardly and this results in rendering the feed rolls ineffective to feed the foil strip during the time this pocket in the carrier disc is moving from the arm 156 to the foil feeding mechanism.

The arm 156 is pivotally connected to a rod 158 which passes loosely through a cylindrical block 159 swiveled on the end of a lever 160 which is pivoted intermediate its ends at 161 on a stationary plate 162 (see also Fig. 18). A coil spring 163 surrounds the rod 158 and is located between a shoulder on this rod and the swivel block 159 on the lever 160. When a piece of candy engages the curved end of the arm 156 this arm is swung in a clockwise direction about its pivot 157 and by means of the rod 158 and the spring 163 swings the lever 160 about its pivot 161 in a counterclockwise direction as viewed in Fig. 1. This causes a pin 164 carried by the end of the lever 160 (Fig. 18) to engage a spring arm 165 on a microswitch 166 and actuate this arm and the switch to thereby break the electric circuit of the solenoid 99 (Fig. 19).

This permits the coil spring 100 (Fig. 19) to swing the arm 98 in a direction to lower the upper feed roll into engagement with the strip of metal foil thereby causing the rotating feed rolls to advance the strip of foil. It will be noted from Figs. 14 and 17 that when the dwell 147 on the cam 146 lifts the cam follower roller 144 and its rocker arm 143 to raise the movable knife blade and sever the foil strip, the arm 149 is also raised because, as above stated, this arm is keyed to the same sleeve 107 on the rocker arm shaft 108

that the rocker arm 143 is keyed to. Therefore, every time the foil strip is severed by the knives a vertical rod 167 (Fig. 14) pivotally connected to the end of the arm 149 is lifted and then immediately lowered.

The upper end of this rod passes through the plate 162. Slidably mounted on the upper end of the rod 167 above the plate 162 is a sleeve 168 on the lower end of which there is a disc 169. A second disc 170 is secured to the extreme upper end of the rod 167, and a coil spring 171 located between this disc and the disc 169 yieldingly urges the latter disc downwardly on the rod 167 into engagement with a shoulder 172 on this rod. If a piece of candy is pressing on the foil-feed control arm 156 and thus holding the arm 160 in a position in which its pin 167 is pressing against the arm 165 of the microswitch (this being the position of the arm 160 shown in Fig. 14), then when the rod 167 is lifted at this time its shoulder 172 will lift the disc 169 and when the rod 167 is again lowered an instant later (before the piece of candy has moved completely past the control arm 156), the disc 169 will return to the position shown in Fig. 14 alongside of the end of the lever 160.

This blocks the movement of the lever 160 and holds it in the position to which it has been moved by the action of the piece of candy pressing on the control arm 156. Thus, even after the piece of candy moves beyond the control arm 156 the lever 160 remains locked in the position to which it has been moved by the piece of candy and the foil strip will continue to be advanced by the feed rolls until the next operation of the cutting knives when the rod 167 will be again raised and lowered. If there is no piece of candy in the pocket of the carrier disc which is passing the control arm 156, upward movement of the rod 167 (Fig. 14) will lift the disc 169 as before but this time the spring arm 165 on the microswitch will swing the lever 160 in a clockwise direction as viewed in Fig. 1 and this will move the curved end of the control arm 156 inward, since there is no piece of candy to hold it in its outward position. When the rod 167 descends, the disc 169 will now strike the upper surface of the end of lever 160 as shown in Fig. 15 and as the rod 167 continues its downward movement the spring 171 will be compressed.

In this position of the parts the microswitch energizes the solenoid 99 (Fig. 19) and lifts the upper feed roll out of contact with the foil strip and thus renders the feed rolls ineffective to advance the foil strip. The parts will remain in this position until a piece of candy again actuates the control arm 156 as above described thus moving the end of the lever 160 back to the position shown in Fig. 14. The coil spring 163 surrounding the rod 158 (Fig. 1) provides a yielding connection between the control arm 156 and the lever 160 so that even though the amount of movement of the lever 160 is limited, the control arm 156 can be moved a greater distance by relatively large pieces of candy than by relatively small ones.

Each piece of candy is moved by the machine from the feed table 3 at the left of Fig. 1 through approximately 450° and is then released by its candy gripping ring 38 so that the piece of candy falls by gravity onto a rotating discharge disc 173 shown in Figs. 1 and 23. This disc rotates about the axis of a vertical rod 174 (Fig. 23) and carries a rubber ring 175 at its periphery which bears against the cam ring 55 that actuates the

wiping blades 56. Thus, rotation of this cam ring causes rotation of the discharge disc 173. As the wrapped pieces of candy fall on this disc they are carried by it in a circular path as shown in Fig. 1 and each piece of candy passes under a yielding rubber covered conical roller 176.

The roller 176 is mounted to rotate freely on a spindle 177 (Fig. 23) which is hinged at 178 to the upper end of the rod 174. An arcuate guard or guide 179 carried by the outer end of the spindle 177 confines the pieces of candy on the rotating disc 173 until they pass under the roller 176. In passing under this roller each piece of candy is subjected to vertical pressure to compress and crease the folds of metal foil under its bottom surface. After the piece of candy passes under the roller 176 a deflector arm 180 (Fig. 1) reflects them off of the rotating disc and into a suitable receptacle. At the inner end of the conical roller 176 there is a conical friction wheel 181 which bears on the upper surface of a friction disc 182 which rotates with the disc 173.

Thus, rotation of the discharge disc 173 imparts rotation to the roller 176, the adjacent surfaces of the discharge disc and the roller moving in the same direction. The lower end of the rod 174 has threaded connection with a stationary bracket 183 and a knurled knob 184 is secured to the rod so that by turning this knob the rod can be adjusted vertically in the bracket. This raises or lowers the conical roller 176, its friction wheel 181, and the friction disc 182 relative to the discharge disc 173. There is thus provided an adjustment by which the size of the gap between the conical roller 176 and the upper surface of the discharge disc 173 may be adjusted to suit the size of the particular pieces of candy being wrapped by the machine.

The operation of the machine will now be described. The pieces of candy to be wrapped by the machine are placed on the feed table 3 (Fig. 1), one such piece of candy being represented at C. The operator presses on the treadle 66 (Fig. 2) in the proper direction to start the machine. As the pockets 10 in the carrier disc 4 (Fig. 1) pass the feed table the operator places one piece of candy in each of the pockets. The path followed by one piece of candy and the operations performed upon it will be described from here on. The carrier disc moves the piece of candy through 180° from the feed table to a position adjacent the foil feeding mechanism.

As the piece of candy is moved past the foil-feed control arm 156 it presses on this arm and causes the upper feed roll (which is continuously rotating with the lower feed roll) to be lowered into contact with the foil strip. A predetermined amount of metal foil will be fed forward by the feed rolls whereupon the cutting knives will operate to cut a piece from the end of the foil strip. If at the time the cutting knives operate, a succeeding piece of candy is pressing on the foil-feed control arm 156 more metal foil will be fed by the feed rolls for this succeeding piece of candy.

If there is a piece of candy in each pocket of the carrier disc the foil-feed control arm 156 will be continuously held in its outward position so that the feeding action of the metal foil will not be interrupted except during the short intervals when the knives sever a piece from the end of the foil strip, but if a piece of candy is not present in any particular pocket of the carrier disc as such pocket passes the foil-feed control arm 156 no metal foil will be fed by the feed rolls

during the time that this pocket travels from the control arm to the foil feeding mechanism.

The parts of the machine are so timed that as much foil is fed inwardly beyond the path of travel of the pieces of candy as exists from such path to the cutting knives. In other words, a piece of candy will be centered longitudinally of a severed piece of foil at the time the piece is cut from the foil strip as depicted in Figs. 8 and 9. When it is desired to wrap relatively large pieces of candy a relatively wide strip of metal foil should be used. Figs. 8 and 9 show respectively relatively narrow and relatively wide strips of foil in the foil feeding mechanism for wrapping relatively small and relatively large pieces of candy.

For relatively large pieces of candy the foil feeding mechanism should feed a greater amount of foil between cutting operations so that more foil will project inwardly beyond the piece of candy to be wrapped, and in order to preserve the symmetrical relationship between the piece of candy and the severed piece of foil the cutting knives should be moved farther away from the path of travel of the piece of candy. In Figs. 8 and 9 it is assumed that the cutting knives have just operated or are just ready to operate. In Fig. 8 the proper amount of metal foil has been fed forward to wrap a piece of candy of the particular size indicated in this figure and the handle 85 (Figs. 19 and 20) has been adjusted to so position the cutting knives that the same amount of metal foil will extend inwardly and outwardly of the piece of candy.

In Fig. 9 the handle 85 has been shifted to a different position to move the cutting knives farther to the right and to cause a greater amount of metal foil to be fed forward by the feed rolls before the strip is severed to preserve the symmetrical relation between the severed piece of foil and the piece of candy to be wrapped. The reason why movement of the handle 85 does both of these things, i. e., shifts the position of the knives and at the same time alters the amount of foil fed forward between cutting operations, will be apparent from Figs. 19 and 20.

When the handle 85 is turned, the cutting knives, the gears 114 that drive the feed rolls, the ball clutches associated with these gears, and the pins 122 on the ball clutches, all move as a unit either to the right or left as viewed in Figs. 19 and 20, while the rocker arms 103 which oscillate on fixed portions of the machine frame remain relatively stationary. Thus, as the handle 85 is turned to move the cutting knives toward the left in Fig. 19, i. e., closer to the path of travel of the piece of candy, the pins 122 on the ball clutches will be moved farther into the slots 104 in the rocker arms 103. Hence, the rocker arms will impart a shorter stroke to the pins 122 and less foil will be fed forward by the feed rolls between operations of the cutting knives.

Adjustment of the cutting knives in the opposite direction by the handle 85 has the opposite effect, namely, movement of the pins 122 outwardly in the slots 104 of the rocker arms 103 to thereby lengthen the stroke imparted to the pins by the rocker arms resulting in a greater amount of foil being fed forward by the feed rolls between operations of the cutting knives. Thus, the closer the knives are to the path of travel of the piece of candy the smaller will be the amount of foil fed forward by the feed rolls between operations of the cutting knives and the farther the cutting knives are adjusted from the path of travel of the piece of candy the greater

will be the amount of foil fed forward between operations of the cutting knives to preserve the longitudinal centered relationship between the severed piece of foil and the piece of candy to be wrapped regardless of the size of the piece of candy.

As a piece of foil is severed from the foil strip the foil gripping fingers 50 (Figs. 2 and 4) are lowered to grip the inner edge of the severed piece of foil against the plate 45. As soon as the piece of foil is severed from the strip of foil it therefore starts moving circumferentially with the plate 45 while the piece of candy being pushed by the carrier disc continues its movement under the severed piece of foil. The piece of candy is now supported on and moving over the thin rectangular plate 72 (Fig. 1). Fig. 26 shows the piece of candy thus moving over the plate 72 under a piece of foil that has just been severed by the cutting knives and that has just been gripped by the gripping fingers 50. In this view the piece of candy is moving away from the reader. At this time the plunger 28 that has reached the foil feeding mechanism is moved upwardly a short distance by a jog or offset 185 in the cam track 24 as shown in the lower part of Fig. 33 at position I.

The amount of upward movement imparted to the plunger by this jog in the cam track brings the head 21 of the plunger very close to the under surface of the thin plate 72 and then the plunger head moves horizontally until it emerges from under this plate. Fig. 27 shows the piece of candy just before it reaches the edge of the thin plate 72 (the movement of the piece of candy in this figure being toward the left) and shows the plunger and its head moving along horizontally under this plate.

It should be remembered that the plungers are moved along in their circular path at a slightly greater speed than the pieces of candy are moved by the carrier disc. In Fig. 27 the plunger therein shown has not quite caught up to the piece of candy moving on the plate 72. However, by the time the piece of candy moves off of the edge of the plate 72 the plunger will have caught up with it and the piece of candy will therefore move onto the head of the plunger as depicted in Fig. 28. Since the plate 72 is very thin and since the plunger head at this time is moving horizontally in close proximity to the under surface of this plate there is no precipitous drop as the candy moves onto the head of the plunger.

At this time a rise 186 in the cam track 24 (Fig. 33) causes the plunger to start rising through the arcuate slot 71 in the surface of the casting 2 under which the plunger has been moving up to this time. The plunger lifts the piece of candy into contact with the severed piece of foil as shown in Fig. 29. At this time the piece of candy is in centered relation with the severed piece of foil transversely of the foil strip. The gripper fingers 50 now release the severed piece of foil and further upward movement of the plunger pushes the piece of candy and the piece of severed foil through the brush ring 26 that is located above the plunger as depicted in Fig. 30 and position II of Fig. 33.

The bristles 27 of the brush ring fold the piece of foil down around the piece of candy. When the plunger reaches the highest position to which it is moved by the rise 186 in the cam track 24 (Fig. 33) the piece of candy and the folded down piece of foil occupy a position in one of the rub-

ber candy gripping rings 33 as depicted at position III of this figure. See also Fig. 31 which shows on an enlarged scale the position of the parts when the piece of candy is in this position.

5 The rubber ring 33 is now open or expanded because the cam rod 39 has been moved up by the rise 187 in the cam track 33 to a point where the cam 31a on this rod is between the rollers 42 on the roller arms 41 thereby moving the lower ends of the arms 37 apart to open the rubber ring. During the next small amount of progression of the cam rod 33 along its circular path from position III it will be raised slightly more by the rise 187 of the cam track 33. This moves the cam 31a 10 above the rollers 42 thus permitting them and the arms 37 to move inwardly and allow the rubber ring 33 to contract and grip the piece of candy as shown in Fig. 32. It should be understood that the rubber ring is of appropriate size 15 to grip, when fully contracted, a piece of candy of given size without squeezing it hard enough to injure it.

The rubber rings may be removed and replaced by another set of rings which are suitable for 20 gripping pieces of candy of the particular kind to be wrapped by the machine. Immediately after the piece of candy is gripped by the rubber ring 33, and during further progression of the plunger 28 along its circular path, a downwardly inclined portion 188 of the cam track 24 lowers the plunger while the piece of candy remains gripped in the candy gripping ring. This is depicted at 25 position IV of Fig. 33. The four corners of the piece of metal foil are now pointing downwardly 30 but it should be noted that in order to bring one of these corners to the leading side of the piece of candy the candy must be rotated $\frac{1}{3}$ of a revolution.

This is accomplished by a stationary pin 189 35 which in position IV of Fig. 33 is about to be engaged by the progressing Geneva wheel 36 which when turned by the pin will also turn all of the arms depending below it and will thus turn the candy gripping ring. The position which this 40 pin 189 occupies circumferentially of the machine is shown in Fig. 3. After the candy gripping ring has progressed a short distance beyond position IV of Fig. 33 the end of the pin 189 will engage the Geneva wheel 36 and turn it $\frac{1}{3}$ of a revolution to bring one of the downwardly extending corners of the metal foil to the leading side of the piece of candy, and as soon as this 45 is accomplished one of the dwells on the cam ring 55 will lift one of the arms 57 carrying a wiper blade 56 and cause this blade to wipe against the forward downwardly extending corner of the metal foil and fold it under against the bottom of the piece of candy. The instant 50 this is accomplished the wiper blade 56 is immediately lowered by the cam ring 55 so that it will not disturb the other downwardly extending corners of the metal foil.

In position V of Fig. 33 the Geneva wheel 36 55 has reached a pair of pins 190 (see also Fig. 3) and in passing these pins the Geneva wheel will be turned two $\frac{1}{3}$ revolutions or 90° to bring the next downwardly extending corner of the metal foil to the leading side of the piece of candy whereupon the next wiper blade 56 is raised and lowered as before to fold under this corner. It will also be noted from position V of Fig. 33 that the plunger 28 has now been lowered far enough by its cam track 24 to bring its head 21 below the 60 top wall of the casting 2 and from hereon to the 65 top wall of the casting 2 and from hereon to the 70 top wall of the casting 2 and from hereon to the 75 top wall of the casting 2 and from hereon to the

starting point the head of the plunger moves horizontally under this wall of the casting.

The operation depicted in position V of Fig. 33 is repeated at positions VI and VII, the Geneva wheel 36 being turned 90° by a pair of pins 191 just after leaving position VI and another 90° by another pair of pins 192 just after leaving position VII, one of the wiper blades 56 serving to fold in one of the downwardly extending corners of the metal foil after each partial revolution until all four of them have been folded in against the bottom of the piece of candy. A single pin 192a (Figs. 3 and 33) imparts a final 1/8 revolution to the Geneva wheel to complete its rotation through 360° and to bring it, and the arms 37 under it, back to their starting position. Each Geneva wheel 36 and the piece of candy gripped by the rubber ring below it, are yieldingly held in the position to which they are turned by the actuating pin or pins by a spring pressed ball 193 (Fig. 2) which engages in one of a circular series of depressions 194 in the upper surface of the Geneva wheel (Fig. 3).

In position VIII of Fig. 33 the cam rod 30 is about to be lowered a small amount by a downwardly inclined portion 195 in the cam track 33. This lowers the cam 31a on the cam rod 30 a sufficient distance to bring it between the rollers 42 (see Fig. 31) and thereby expand the rubber candy gripping ring 38 and allow the wrapped piece of candy to fall on the rotating discharge disc 173. As shown at the right end of Fig. 33 a further downwardly inclined portion 196 in the cam track 33 lowers the cam rod 30 far enough to cause it to eject the wrapped piece of candy from the rubber candy gripping ring if it should not fall therefrom by gravity when the ring is expanded, this occurring before the parts reach position III in which another piece of candy is pushed up into the candy gripping ring. Each wrapped piece of candy is subjected to light vertical pressure by the yielding roller 176 as the piece of candy is moved under it by the discharge disc 173. This compresses and creases the folds of metal foil under the piece of candy and then the candy is discharged from the machine by the deflector arm 180 (Fig. 1) as above described. After the downwardly extending corners of metal foil are folded under the piece of candy and compressed by the roller 176 they stay in the position to which they have been folded. If another kind of wrapping material is used such as paraffin paper or thin sheet plastic, the wiper blades 56 may have heating devices associated with them whereby the paraffin or plastic material is melted sufficiently each time one of the downwardly extending corners of the piece of wrapping material is folded under the piece of candy to cause the corners to remain in their folded position when the melted material again cools.

The machine has a large capacity since it handles a large number of pieces of candy at one time and since the pieces of candy have a progressive movement through the machine without interruption at any time. It is designed to handle fragile pieces of candy which are ordinarily difficult to wrap without injuring them. The machine has sufficient adjustments and replaceable parts to adapt it for use in wrapping different lots of candy in which the pieces in one lot differ in size, within certain limits, from those in another lot. Even the foil feeding mechanism is adjustable to feed and cut the foil in accordance with the size of the particular pieces of candy being wrapped.

The invention is described in connection with one particular embodiment, wherein the various features of the invention are illustrated by way of example, and it will be understood that changes in the construction and operation of the various parts of the disclosed machine may be made without departing from the spirit of the invention, and that the scope of the invention is set forth in the appended claims.

I claim:

1. In a machine for wrapping pieces of candy and the like having a circular series of candy handling and wrapping devices which revolve about a common axis and having feeding mechanism for feeding wrapping material toward the circular path along which said devices move, the combination therewith of a rotary carrier having a circular series of pockets each adapted to receive one of the pieces of candy to be wrapped, the circular path along which said devices move having a smaller radius than and being in eccentric relation to the circular path along which said pockets move, and the circular path of said devices lying within the circular path of said pockets except where the devices and the pockets pass said feeding mechanism for the wrapping material where portions of the two circular paths lie one over the other.
2. In a machine for wrapping pieces of candy and the like having a circular series of candy handling and wrapping devices which revolve about a common axis, a feed table for supporting the pieces of candy to be wrapped, and feeding mechanism at the opposite side of the machine from said feed table for feeding wrapping material toward the circular path along which said devices move, the combination therewith of a rotary carrier having a circular series of pockets each adapted to receive one of the pieces of candy to be wrapped, the circular path along which said devices move having a smaller radius than and being in eccentric relation to the circular path along which said pockets move, and the circular path of said devices lying within the circular path of said pockets except where the devices and the pockets pass said feeding mechanism for the wrapping material where portions of the two circular paths lie one above the other, the portion of the circular path of said pockets which lies the greatest distance outwardly of the corresponding portion of the path of said devices being the portion which is adjacent said feed table.
3. A machine in accordance with claim 1, in which the number of said handling and wrapping devices in the circular series is less than the number of pockets in said rotary carrier, the machine having means for rotating the carrier and the series of devices at different speeds and at a speed ratio equal to but in inverse relation to the ratio between the number of pockets in the carrier and the number of said devices in the circular series.
4. A machine for wrapping pieces of candy and the like in metal foil comprising a circular series of candy handling and wrapping devices which revolve in unison about a common axis, said devices including a circular series of vertically movable plungers, foil-brushing means located above each plunger, candy gripping means located above each foil-brushing means, each candy gripping means being rotatable about its own axis, means for feeding a strip of metal foil transversely across the circular path of movement of said devices, cutting means for sev-

ering from the main strip of foil the end portion thereof that intersects such path, a severed piece of the foil being delivered by the feeding and cutting means to a position above each plunger as it reaches a position in front of the feeding and cutting means, gripping means adjacent each plunger and revolving therewith about said axis for gripping the severed piece of foil to cause it to revolve with such plunger, means for depositing a piece of candy on the upper end of each plunger, means acting during revolution of the plungers about said axis for moving each plunger with its piece of candy upwardly to bring the piece of candy into contact with the severed piece of foil and to push the candy and such piece of foil through the corresponding foil-brushing means to fold the foil down around the piece of candy and then push the piece of candy and the folded down foil into the corresponding candy gripping means, means then acting on such candy gripping means to render it effective to grip the partially wrapped piece of candy, means acting during further revolution of the plungers about said axis for lowering each plunger after the corresponding candy gripping means has gripped the piece of partially wrapped candy moved upwardly by it, means operating during revolution of the candy gripping means about said axis for acting on each candy gripping means after it has gripped a piece of partially wrapped candy to impart a partial revolution to it about its own axis at a series of successive positions, means operating after each partial revolution of the candy gripping means to fold in against the bottom of the piece of candy one of the downwardly extending corners of the metal foil, and means for discharging the wrapped piece of candy from the machine after all of such corners of the foil have been thus folded in.

5. A machine in accordance with claim 4, in which each of said foil-brushing means comprises a brush ring which has inwardly extending bristles and through which a piece of candy and a piece of foil is pushed by one of the plungers to fold the foil down around the piece of candy.

6. A machine in accordance with claim 4, in which each of said candy gripping means comprises a plurality of downwardly extending arms pivotally supported at their upper ends, the machine having cam means acting on said arms during their revolution about said axis to move their lower ends toward and away from a piece of candy moved to a position between them by one of said plungers.

7. A machine in accordance with claim 4, in which each of said candy gripping means comprises a plurality of downwardly extending arms pivotally supported at their upper ends and a resilient ring carried by the lower ends of the arms, the machine having cam means acting on said arms during their revolution about said axis to move their lower ends toward and away from a piece of candy moved to a position between them by one of said plungers, the resilient ring being connected to the lower ends of said arms so that when they are so moved by said cam means the resilient ring expands and contracts to grip or release the piece of candy.

8. A machine in accordance with claim 4, in which said means for folding in the downwardly extending corners of the metal foil comprises a series of wiper elements each adapted to engage one of said corners of the foil when it is at the leading side of the piece of candy and fold it in.

5 during movement of the piece of candy, and in which said means that imparts partial revolution to each candy gripping means at successive positions thereof first imparts an eighth of a revolution to the candy gripping means to bring one of the downwardly extending corners of the metal foil to the leading side of the piece of candy and thereafter imparts a series of partial revolutions to the candy gripping means through 90° to bring the other downwardly extending corners of the metal foil successively to the leading side of the piece of candy.

10 9. A machine in accordance with claim 4, in which said means for depositing a piece of candy on the upper end of each of the plungers comprises a stationary support under which the series of plungers move during part of their progression around said axis and having an opening through which each plunger is moved upwardly by said plunger-moving means as it reaches a predetermined position during its progression, carrier means having a series of pockets each adapted to receive a piece of candy, and means for actuating the carrier means to move the pieces 15 of candy along the surface of said support and deposit them successively on the upper ends of the plungers as they rise through said opening in the support.

20 10. A machine in accordance with claim 9, in which said carrier means comprises a disc in which said pockets are formed and which rotates about an axis in eccentric relation to the axis about which the plungers revolve, the circular path followed by the plungers lying within the 25 circular path followed by said pockets except where the pieces of candy are deposited on the ends of the rising plungers at which place the circular path of said pockets lies over the circular path of the plungers.

30 11. A machine in accordance with claim 4, in which said means for feeding a strip of metal foil transversely across the circular path of movement of the candy handling and wrapping devices comprises a pair of feed rolls and driving means for rotating them, said feed rolls and the cutting means being mounted for bodily movement in unison toward and away from said circular path, the machine having means for adjusting the feed rolls and the cutting means toward and away from said circular path, and means interposed in the feed roll driving means for varying the amount of foil fed forward by them in a given period of time when the position of the feed rolls and the cutting means is adjusted by said adjusting means.

35 12. In a wrapping machine having article handling and wrapping devices movable along a predetermined path, the combination therewith of feeding mechanism for feeding a strip of wrapping material transversely across the path of travel of said devices, said feeding mechanism comprising a fixed frame, a pair of feed rolls between which the strip of wrapping material passes, cutting knives located between the feed rolls and said path along which said devices move, the feed rolls and the cutting knives being movably mounted on said frame for movement in unison toward and away from said path, means for driving the feed rolls, and means for adjusting the feed rolls and the cutting knives toward and away from said path, said driving means for the feed rolls including parts that are adjusted when the position of the feed rolls and the cutting knives is adjusted to impart a greater amount of rotation to the feed rolls and cause

25

them to feed a greater amount of wrapping material in a given period of time when the feed rolls and cutting knives are adjusted away from said path than when they are adjusted toward said path and vice versa.

13. Feeding mechanism for feeding sheet material transversely across a given path comprising a fixed frame, a pair of feed rolls between which the sheet material passes, a pair of cutting knives between the feed rolls and said path, the feed rolls and the cutting knives being movably mounted on said frame for adjustment in unison toward and away from said path, driving means for rotating the feed rolls, and means for adjusting the feed rolls and the cutting knives toward and away from said path, the driving means for the feed rolls including parts which are adjusted when the position of the feed rolls and the cutting knives is adjusted

26

to vary the amount of rotation of the feed rolls so that they feed more sheet material in a given period of time when the feed rolls and cutting knives are adjusted away from said path and a smaller amount in an equal period of time when they are adjusted toward said path.

THEODORE F. SCHLICKSUPP.
